UNITED STATES PATENT OFFICE

125,601

DESIGN FOR A DOOR GRILLE OR SIMILAR ARTICLE

Dallas Emery Walker, Tampa, Fla., assignor of one-half to Donald Everett Walker, Tampa, Fla.

Application October 4, 1940, Serial No. 95,649

Term of patent 14 years

To all whom it may concern.

Be it known that I, Dallas Emery Walker, a citizen of the United States of America, residing at Tampa, in the county of Hillsborough, State of Florida, have invented a new, original, and ornamental Design for a Door Grille or Similar Article, of which the following is a specification, reference being made to the accompanying drawing, forming part thereof.

my new design with the double action end adjustments in an adjusted position.

Figure 2 is a similar view thereof showing the double action end adjustments in another adjusted position.

I claim:

The ornamental design for a door grille or similar article, as shown and described.

DALLAS EMERY WALKER.
